UNITED STATES PATENT OFFICE

164,682

COCKTAIL TABLE OR THE LIKE

Frederick Bruce Forward, McGaheysville, Va.

Application April 1, 1949, Serial No. 1,751

Term of patent 14 years

(Cl. D33—14)

To all whom it may concern:

Be it known that I, Frederick Bruce Forward, a citizen of the United States, residing at McGaheysville, in the county of Rockingham and State of Virginia, have invented a new, original, and ornamental Design for Cocktail Table or the Like, of which the following is a specification, reference being had to the accompanying drawing, forming part thereof.

Fig. 1 is a side view of a cocktail table or the like, showing my new design.

Fig. 2 is an enlarged top view thereof.

Fig. 3 is an enlarged detailed fragmentary view of a corner portion of the table top shown in Fig. 2.

Fig. 4 is a detailed cross-sectional view taken on the line 4—4 of Fig. 3.

My design is characterized by the ornamentation on the table top.

I claim:

The ornamental design for a cocktail table or the like, as shown and described.

FREDERICK BRUCE FORWARD.
